UNITED STATES PATENT OFFICE.

YAZO NAKAMURA, OF OSAKA, JAPAN.

DEVICE FOR SHIPPING AND DISCHARGING CARGO.

Application filed December 22, 1919. Serial No. 346,652.

To all whom it may concern:

Be it known that I, YAZO NAKAMURA, citizen of Japan, residing at No. 448 Nishinoda-cho, Kita-ku, Osaka, Japan, have invented certain new and useful Improvements in Devices for Shipping and Discharging Cargo; and I do hereby declare the following to be a full, clear, and exact description of the invention, such as will enable others skilled in the art to which it appertains to make and use the same.

This invention relates to an arrangement for shipping and discharging cargo, in which arrangement cargo-beams with a travelling carriage are horizontally suspended from a rope that is stretched out between two mast-heads, or in absence of which, between two upstanding poles.

The invention has for its object to have the weight of packages to be handled to bear most on the centre line of a ship, instead of bearing on the traverse or oblique direction from it as is the case hitherto, in order that by sufficing with a fewer number of shrouds supporting the mast the ship's construction can not only be simplified but the passage of packages in and out of the ship can be made greatly freer on account of having a larger open space produced by reduction of shrouds.

The accompanying drawings show an embodiment of the invention. Fig. 1 is a side elevation of a ship equipped with cargo-beams according to the invention. Fig. 2 is a plan; Fig. 3 is an end view of same. Fig. 4 shows a side elevation of a mast or a post; Fig. 5 is a sectional view of same. Fig. 6 is a detail of a cargo-beam; Fig. 7 is its sectional view, while Fig. 8 is its modification. When reference is to be made to the accompanying drawings, the same letters indicate same or similar parts in all the figures.

When a package is to be shipped into or discharged from a ship's hold, it is hooked up to a suitable height by means of a travelling carriage *l*, which is equipped on a cargo-beam *h*. The cargo-beam is held in a horizontal position with ropes *g*, said ropes, in turn, being suspended from another rope *e*; the latter is guided by rope pulleys *f* fixed on masts or posts *c*. The raising or lowering of a package is regulated with the rope *r*, which is wound or unwound by a winch *b*, so as to suit the case.

The lower ends of the rope *e* are fixed to

suitable points of the deck, and the position of the cargo-beam may be changed fore or aft by pulling the rope *e* by a winch, *b*.

When a package is held at the end of the cargo-beam, it is inferable that the loaded end will lower itself over the ship's side as shown in Fig. 3. Guys *K*, however, are fastened to the other end of the beam to prevent the dropping of the loaded end, and ropes *j* are also fixed to the same to avoid its swinging motion. The carriage *l* travels along the beam to and fro by means of the rope *g*, which is wound reversibly on a winch *b*. The vertical motion of the hook is regulated by the rope *r*, which is guided by rope pulleys *m* and *n* and is wound up with the winch *b*, while its horizontal motion is regulated by the rope *q*, which is guided by pulleys *p* and is wound up by the winch *b*.

According to this invention, the weight of packages bears in the direction of the centre line of the ship, the bending of masts or posts in transverse direction is very slight. The rope *d* is stretched out from the bow to the stern part binding the mast-heads or posts, and a single shroud *i* on either side of them (masts or posts) will be sufficient to support them against the weight of packages. It is to be noted that with my invention the weight of the cargo-beam and the packages which it is adapted to lift is exerted on the masts or supports entirely in a line or plane between the masts at all times, consequently it is only necessary to brace the masts in this line. A large number of the usual bracing shrouds radiating in all directions to brace the mast may therefore be dispensed with.

Further, masts or posts of the known type must be built very strong in order to stand the strain of packages hanging in radial directions, while in the present invention, they need not be very strongly built. A combination of angle and flat bars will suffice; an example is shown in Figs. 4 and 5. They are perfectly safe. They are not required to bear strain transversely.

After unfastening the quay-ropes *k* and *j*, the cargo-beam may be turned around to the other side of the ship, and, when the beam is not in use, it is lowered to the deck at a right angle to the serving position, as shown with chain lines in Fig. 1. In this position the cargo-beam may be used as a pole for a tent to cover the hatchway.

What I claim is:—

1. An arrangement for shipping and discharging cargo, comprising a cargo-beam hanging horizontally from a rope, said rope being guided by rope pulleys fixed on masts or posts with a means to pull the rope in opposite directions in order to alter the position of the cargo-beam, fore or aft, means provided on the cargo-beam to lift up packages of cargo, and means for positively shifting packages of cargo to and fro on said cargo-beam.
2. Loading and unloading apparatus comprising in combination, two supports, hoisting means, means for positively shifting weights to and fro transversely of said supports and means secured to said supports to support said hoisting means and said shifting means between said supports, the weight supported always exerting a force on said supports in substantially the same direction.
3. Loading and unloading apparatus comprising, in combination, two supports, hoisting means, means for positively shifting weights to and fro transversely of said supports and flexible means secured to said supports to support said hoisting means and said shifting means between said supports.
4. Loading and unloading apparatus comprising, in combination, two supports, hoisting means, means for positively shifting weights to and fro transversely of said supports, and means connected to said supports for supporting said hoisting means and said shifting means, said supporting means being movable to alter the position of said hoisting means and said shifting means longitudinally with respect to said supports.
5. Loading and unloading apparatus comprising in combination, two supports, a cargo-beam, flexible means connected to said supports and said cargo-beam for supporting said cargo-beam between said supports, means on the cargo-beam for lifting loads, and means on said cargo-beam for positively shifting loads back and forth along said cargo-beam.
6. Loading and unloading apparatus comprising, in combination, two supports, a cargo-beam, flexible means connected to said supports and said cargo-beam for supporting

said cargo-beam between said supports, a carriage adapted to travel along said cargo-beam, means for positively moving said carriage back and forth along said cargo-beam, and means on said carriage to raise a load. 55

7. Loading and unloading apparatus comprising, in combination, two supports, a cargo-beam, means for supporting said cargo-beam from said supports, a carriage adapted to travel along said cargo-beam, means for moving said carriage to and fro along said cargo-beam and adapted to hold said carriage at any point along the cargo-beam, and means on said carriage to raise a load. 60 65

8. Loading and unloading apparatus comprising, in combination, two supports, a cargo-beam, means for supporting said cargo-beam from said supports, said means being movable to move said cargo-beam vertically and horizontally with respect to said supports, means on the cargo beam for lifting loads and means on the cargo-beam for positively shifting loads back and forth along said cargo-beam. 70 75

9. Loading and unloading apparatus comprising the combination with a ship provided with masts, of means for raising cargo, means for positively shifting cargo back and forth transversely of the ship, and flexible means connected to two of said masts for supporting said cargo-raising means and said shifting means between said masts. 80

10. Loading and unloading apparatus comprising the combination with a ship provided with masts, of means for raising cargo, means for positively shifting cargo back and forth transversely of the ship, and means connected to two of said masts for supporting said cargo raising means and said shifting means between said masts whereby the weight of said cargo raising means and said shifting means is exerted on said masts principally longitudinally of the ship. 90 95

In testimony whereof I hereunto affix my signature in the presence of two witnesses.

YAZO NAKAMURA.
